Design of the "Empress Barker"
By J. M. F. Barker or John M. F. Barker
designer to Messrs. Barker, Yaff & Yorom.

No. 779

Des. 779

N. S. Beddoe & Wm L. Sanderson of Troy, N. Y.

Assignors to

Sanders, Wolfe & Warren of Troy, N. Y.

Letters Patent No. 779. Dated April 8. 1856.

The schedule referred to in these Letters Patent, and
making part of the same.

To all whom it may concern:

Be it known, that we, N. S. Beddoe
and Wm L. Sanderson, each of the City of Troy, in the County
of Rensselaer and State of New York, have jointly invented
or produced a new and original design for a parlor stove,
which we call the "Congress Parlor"; and we do hereby de-
clare that the following is a full, and exact description
of the same, reference being had, by letters, to the annexed
isometrical drawing, making a part of this specification.

Our said design consists of the ornamental
leg A; the bottom plate B - embracing the clamps

2

Ms. 779

plate B' - having the scroll-work border a, and the ornamented base-moulding b; the front plate C, of the lower section of the stove having the foliage ornaments c, c' and d, d'; The ornamented projecting mouldings e & f, and the ornamented recesses; the ornamented damperslides D, and E'; the side plate F, of the lower section, having the ornamented projecting mouldings g and h, with the boss i; The compositions of foliage j, and k, and the ornamented bases l, l'; The combination of columnar and other mouldings, and ornaments in the bent fire-door G; the top plate H, of the lower section, having the ornamented border m; the upper front plate I, having the foliage ornaments n, n'; and a combination of various ornaments and mouldings, on the central and upper portion thereof; the curved upper side plate J, having the panel of mouldings o, at its base, and a combination of mouldings and ornaments above; the bent top plate K, having the border moulding q, the inner ornamented moulding p, and the leaves r, r'; and the ornamented run L.

Having thus described our ornamental design for a parlor stove; What we claim as new and desire to secure by letters patent is; the ornamental design and configuration of the stove plates herein described and represented in the annexed drawings.
